CLOCK CASE OR SIMILAR ARTICLE

Filed Dec. 19, 1931

Inventor:
Henry T. Schiff
By Maud S. Bayr
Atty.

UNITED STATES PATENT OFFICE

HENRY T. SCHIFF, OF CHICAGO, ILLINOIS

DESIGN FOR A CLOCK CASE OR SIMILAR ARTICLE

Application filed December 19, 1931. Serial No. 42,154. Term of patent 3½ years.

To all whom it may concern:

Be it known that I, HENRY T. SCHIFF, a citizen of the United States, and resident of Chicago, in the county of Cook and State of Illinois, have invented a new, original, and ornamental Design for a Clock Case or Similar Article, of which the following is a specification, reference being had to the accompanying drawing, forming a part thereof.

The figure is a front perspective view of a clock case or similar article showing my new design.

I claim:

The ornamental design for a clock case or similar article as shown.

Signed at Chicago, in the county of Cook and State of Illinois, this 1st day of December, A. D. 1931.

HENRY T. SCHIFF.
